THEODORE C. ROBERTS, OF NEW YORK, N. Y., ASSIGNOR TO COLUMBIA GRAPHOPHONE MANUFACTURING COMPANY, OF BRIDGEPORT, CONNECTICUT, A CORPORATION OF DELAWARE.

METHOD AND APPARATUS FOR PRESSING DISK SOUND RECORDS WITHOUT THE AID OF HEATING AND COOLING MEDIUMS.

Application filed May 6, 1921. Serial No. 467,364.

To all whom it may concern:

Be it known that I, THEODORE C. ROBERTS, a citizen of the United States, and a resident of the city of New York, county and State 5 of New York, have invented certain new and useful Improvements in Methods and Apparatus for Pressing Disk Sound Records Without the Aid of Heating and Cooling Mediums, of which the following, taken 10 in connection with the accompanying drawings, is a specification.

This invention relates to an improved method of pressing phonograph records of disk type from thermoplastic composition, 15 and more especially to the press equipment and the form of matrix used in this improved method.

A principal object of this improvement is to provide a matrix shell adapted to be 20 heated solely by the heat from the record material, thereby eliminating the usual complicated press equipment required for heating the matrices after each record has been pressed and removed, and prior to the introduction of the material for the next record.

Another object is to provide a matrix shell which will also allow the plastic record to be quickly cooled in the press sufficiently to be safely removed therefrom and 30 without the use of cooling water with its complicated press equipment.

Finally, an object is to reduce to a minimum the time required to manufacture each 35 record.

These and other objects will be more fully brought out in the following specification, illustrated in the drawings, and covered in the appended claims. For clearness, three modified forms of the improved 40 matrix are shown, each embodying the principle of this invention.

In order to more fully bring out the working features and advantages of this invention, a brief outline of the present method 45 of manufacturing such records will be first considered.

The records are pressed from a "matrix," which is simply an electrotype in the nega-

tive of an ordinary wax record containing the original tone-lines. The matrix being relatively thin, in order to impart the necessary rigidity for press use, a relatively thick copper plate is soldered or otherwise fastened to its back. This reinforced matrix 50 is then removably secured between steel dies attached to the platens of a hydraulically-operated press. A title-label is placed over the center pin of the matrix; then a biscuit-shaped mass of the record material, 55 which has been previously heated to a plastic consistency, is placed between the matrices, which have been heated to prevent premature chilling of the material. The press is then actuated to bring together the 60 matrices and so form the record between them. Finally, the pressed record is hardened while still under compression in the closed press, by circulating cold water through enclosures or water jackets which 65 are placed as near as possible to the matrices. When the record has hardened sufficiently to permit of its removal from the press, the cold water is turned off and the 70 record taken out. Steam is then admitted 75 to the platens in place of the cold water and serves as a heating medium to again raise the temperature of the platens and their matrices preparatory to the introduction of the heated material for the next record. 80 These alternate heating and cooling operations not only necessitate the use of complicated and expensive machine equipment for introducing and discharging the heating and cooling media, but moreover, they 85 consume valuable machine time, and greatly cut down quantity production; for the operator's time is almost entirely taken up both in heating the record material preparatory to inserting it in the press and in cooling 90 and finally removing the hardened record.

The method and structure embodied in this invention accomplishes the purpose sought in a far simpler and more effective way than anything heretofore attempted, it 95 being based upon the discovery that externally applied heating and cooling media are entirely unnecessary to the rapid produc-

tion of records. A brief outline of the probable phenomena, which take place in the manufacture of records, is as follows:

Since it is necessary to heat the record stock before it is introduced into the press in order to obtain the initial degree of plasticity required, no further heating either of the matrices or press platens would be necessary but for the fact that the complete matrices with their supporting backs and press platens present a considerable heat-containing reservoir of metal into which the relatively small heat content of the record material is quickly dissipated; likewise when the operation is reversed and the cooling medium turned on, the time interval necessary to cool the record sufficiently to permit its safe removal from the press is increased because of this relatively large metal which has absorbed the heat.

This action being as described, I have discovered that any means for shortening the time-interval of heat transference from the record stock to its container will decrease the time of making the record. The invention here disclosed not only accomplishes this result, but in addition thereto, it eliminates the expensive press equipment now used for this alternate heating and cooling of the matrices.

The improved matrix structure used with this new method will be understood by reference to the annexed drawing, in which—

Figure 1 is a cross section of one form of the matrix with its supporting die, and taken through a diameter thereof, as through line A—A of Fig. 4;

Fig. 2 is a partial or broken-away view of a similar cross section of a modified form of the invention;

Fig. 3 is a view, similar to Fig. 2, of still another modification; and

Fig. 4 is a perspective view of the complete matrix structure with its reinforcing back.

Like numerals refer to like parts throughout the several views.

The matrix shell, or electrotype, is indicated by numeral 1, its inner edges which surround a center cut-out portion, being flanged downward or bent at right angles to the surface of the matrix, as shown at 1^a.

This record-forming shell 1, minus the thick copper plate usually soldered thereto, is then mounted in a supporting die or plate 3 formed of a relatively thick plate of steel. Between the matrix shell 1, and the supporting plate 3 is placed a heat-insulating means, indicated by numeral 2 of Fig. 1. This insulating means consists of one or more thin layers of any good relatively incompressible insulating media, such as pressed asbestos, fibre, etc. Fig. 1 shows but one relatively thick sheet 2 of this insulation; Fig. 2 shows three thin layers 10; and

Fig. 3 shows three still thinner layers 11, separated by metallic laminations 13. This last arrangement is advantageous in that it provides a less yielding backing between the matrix and its support, and it further alters the specific heat of the material, this possibly being of value in some cases. It will, of course, be apparent that by varying the number, position, and character of the insulating media used, various thermal resistivities—or conductivities—and specific heats, and ratios there-between, may be effected.

In this way there is obtained an almost complete control over the thermal conditions throughout the process of manufacture, without resort to auxiliary means. For any desired condition can be obtained by merely altering the ratios between the thermal conductivity of the matrix structure and the thermal capacities of (1) the record material, (2) the matrix-shell, (3) the matrix-support, and (4) the insulating material; or (5) various combinations and permutations of these ratios. Again, by this means there is obtained a control over both the initial and final temperatures at different parts of the pressing apparatus, and over the time interval required for the heat flow to or from the different parts.

It will be further noted that this matrix structure can be so proportioned as to obtain and hold substantially the same temperature at each instant, as has the hot record stock in contact with it, until the record material has cooled sufficiently to allow its removal. This is accomplished by merely proportioning and distributing the thermal capacities and conductivities of various parts of the matrix structure, as described, until this condition obtains. Thus the matrix shell is initially raised to a temperature of about 225° F., being heated from the heat of the record stock; and as heat is diffused through the insulating media and the record material gradually cools, the matrix is maintained at substantially the same temperature as the record material until the record is removed. In this manner the use of auxiliary heating and cooling apparatus is eliminated.

From the above, it will be seen that the matrices and the record-material may be pre-heated to conjointly supply the heat units necessary to make the material plastic. The heat stored in the matrices may, as above pointed out, be supplied by direct heat-transference from the record-material in the previous pressing operation, or it may be applied to the matrices in other ways—by an electric stove, such as is used for heating the record-material, for instance. Further, the matrices alone may be heated to have stored-up in them the heat units necessary to make the record-material plastic, and to

themselves remain at the temperature necessary for proper molding, the record-material being supplied to the matrices at or about room temperature.

Considering the above facts in the light of present-day manufacturing methods, the vast significance of this discovery will be readily apparent.

The center of the supporting plate 3 is preferably cored to receive a matrix-securing means comprising a disk sleeve 6, a fastening nut 8 screwing into a clamping nut 9, said clamping nut having a conical-shaped threaded outer surface adapted to expand the outer periphery of expanding-ring 7 against the flanged rim 1^a of the matrix shell and thereby position it firmly at its center.

The outer periphery or rim of shell 1 is firmly secured to its supporting die 3 by means of a clamping ring 4, slightly overhanging the matrix and with its bearing face under-cut so as to provide an edge contact, as shown. This clamping ring is secured to the supporting die 3 by means of stud bolts 5, and is so shaped as to allow its inner edge to bear along the matrix rim, and its outer edge along the outer periphery of the circular recess of the supporting plate 3, leaving space 12 between the central portion of ring 4 and plate 3.

It has been found that the best results are obtained when the thickness of the insulating material between the supporting die and matrix is approximately five-hundredths of an inch, and when the temperature of the matrix at the time of placing the hot record material thereon and before its temperature is raised by heat from the record material is around 120° F. This latter condition may be realized after the initial pressing by quick manipulation in removing the hardened record from its mold (the record being sufficiently hard to permit its removal at said temperature) and placing a fresh batch of record material on the matrix and then quickly subjecting it to pressure.

This invention makes possible the immediate removal of the record from the press, instead of its retention therein for cooling as now practised, the final cooling or hardening of the record occurring outside of the press. This permits of the press being used solely for performing its primary function—namely, pressing.

A time interval of some thirty to forty seconds has been found sufficient to effect cooling of a pressed record to a point where it may safely be handled without buckling. This time interval is considerably less than that consumed with the present method employing cooling water; hence the saving of expense claimed for this improved method. Moreover, it is determined that this method gives a superior gloss to the records and

eliminates their sticking to the matrix after pressing. Then, too, important corollary advantages resulting through the use of this new method include a very considerable saving in boiler horse power due to decreased steam consumption, and greatly improved working conditions in the press room, due to lessened heat radiation.

It will be understood, of course, that this method can be used equally well either in presses with hand-removed-and-inserted matrices, or in presses where the matrices are secured to the press platens.

Having thus set forth the nature of the invention, what is claimed herein is:

1. In the manufacture of sound records and the like, the method of forming the records, which includes molding them between matrices heated solely by heat from the record stock.

2. A means of retaining the heat in the material while on a forming matrix, which includes the step of treating the material within a mold wherein the matrix-shell is thermally insulated from its support.

3. A means of retaining the heat in the material while on a forming matrix, which includes the step of treating the material within a mold wherein the matrix-shell and its support have interposed between them material of greater specific heat than the matrix.

4. A means of retaining the heat in the material while on a forming matrix, which includes the step of treating the material within a mold wherein the matrix and its support have interposed between them material of greater specific heat than either the matrix or its support.

5. A means of retaining the heat in the material while on a forming matrix, which includes the step of treating the material within a mold wherein the matrix and its support have interposed between them material of lesser thermal conductivity than either.

6. In the manufacture of sound records and the like, the method of molding the records which includes the step of treating the record-material within a mold wherein the matrices are heated solely by the heat of the record stock, and wherein each matrix is thermally insulated from its support.

7. A means of cooling thermoplastic material from a plastic to a hardened state while on a form-imparting matrix, which includes the step of treating said material within a mold wherein the heat of plasticity is dissipated by absorption through the matrix into heat-insulating material therebehind and into a support for the same.

8. A means of hardening a thermoplastic sound record, which includes the step of treating the material within a mold wherein the forming surface or shell of the record-

forming member is thermally insulated from its supporting back, to reduce to a minimum the absorption of heat by the record-forming member.

5 9. In the manufacture of molded articles, the method of molding which includes the step of treating heated material in a mold, the matrices of which are heated solely by the heat of the material.

10 10. In the manufacture of molded articles, the method of molding which includes the step of treating heated material in a mold, only the matrices of which are heated by the heat of the material.

15 11. A sound-record matrix comprising a thin record-forming shell separated from its support by thermal-insulation.

20 12. A sound-record matrix including a thin record-forming shell separated from its support by material of greater specific heat.

25 13. An apparatus for cooling record-forming material from a plastic state, comprising a shell matrix, a support therefor, and heat-insulating material between the matrix and support.

30 14. A molding-press matrix including a forming-shell, a support therefor, and heat-insulation between the shell and support.

35 15. A molding-press matrix comprising a forming-shell, a support therefor, and heat-insulation between the shell and support and forming a part of the support.

40 16. A matrix structure for pressing sound records, comprising a forming-shell, a support therefor, and a series of adjacent heat-insulating layers between the shell and support, and forming a part of the support.

45 17. A matrix structure for pressing sound records, including a forming-shell, a support therefor, and a series of adjacent layers of various thermal resistivities between the shell and support, and forming a part of the support.

50 18. A matrix structure for forming sound records and the like, comprising a forming-shell, a support therefor, and a series of heat-insulating layers between the shell and support, and forming a part of the support, said layers being separated by metallic laminations.

55 19. The invention as in claim 15, in which the outer periphery of the shell is secured to its support by means of a removable clamping member.

60 20. The invention as in claim 19, in which the clamping member is adjustable.

21. A method of manufacturing sound records and the like, including maintaining the matrices at an approximately constant 65 temperature throughout the operation.

22. A sound-record matrix adapted to retain an approximately constant temperature while in use, comprising a thin forming-shell separated from its support by material of greater specific heat.

23. A sound-record matrix adapted to retain an approximately constant temperature while in use, comprising a thin forming-shell separated from its support by material of lesser thermal conductivity.

70 24. A sound-record matrix adapted to retain an approximately constant temperature while in use, comprising a thin forming-shell separated from its support by material of greater specific heat and lesser thermal conductivity.

75 25. In an apparatus for pressing thermoplastic articles, a matrix and a support thermally insulated therefrom, whereby the escape of the heat from the thermoplastic material will be retarded.

80 26. A method of manufacturing sound records, including maintaining the matrix support at a practically constant temperature throughout the operation.

85 27. A sound-record forming-matrix which will quickly assume and hold substantially the same temperature as is given to the record stock.

90 28. A matrix for pressing hot thermoplastic material, having its thermal capacity so proportioned and distributed that it initially assumes the temperature of the hot thermoplastic material.

95 29. A matrix for pressing hot thermoplastic material, having its thermal conductivity so proportioned and distributed that it initially assumes the temperature of the hot thermoplastic material.

100 30. A matrix for pressing hot thermoplastic material, having both its thermal capacity and its thermal conductivity so proportioned and distributed that it initially assumes the approximate temperature of the hot thermoplastic material.

105 31. A matrix for forming hot thermoplastic material, having its thermal conductivity so proportioned and distributed to the thermal capacity of the thermoplastic material that the matrix initially assumes the temperature of the hot thermoplastic material.

110 32. A matrix for forming hot thermoplastic material, having its thermal conductivity so proportioned and distributed to the thermal capacity of the thermoplastic material that the matrix initially assumes the approximate temperature of the thermoplastic material, and ultimately cools the same.

115 33. A matrix for forming hot thermoplastic material, the thermal conductivity of the matrix and the thermal capacity of the matrix-shell so proportioned and distributed that it initially assumes the temperature of the hot thermoplastic material.

120 34. A matrix for forming hot thermoplastic material, the thermal conductivity of the matrix and the thermal capacity of the matrix-shell so proportioned and dis-

tributed that it initially assumes the approximate temperature of the hot thermoplastic material, and ultimately cools the same.

5 35. A matrix for forming hot thermoplastic material, the thermal conductivity of the matrix and the thermal capacity of the matrix-support so proportioned and distributed that it initially assumes the temperature of the hot thermoplastic material.

36. A matrix for forming hot thermoplastic material, the thermal conductivity of the matrix and the thermal capacity of the matrix-support so proportioned and distributed that it initially assumes the approximate temperature of the hot thermoplastic material, and ultimately cools the same.

37. A matrix for forming hot thermoplastic material, comprising a matrix-shell and a matrix-support separated by thermal insulation, the thermal conductivity of the matrix and the thermal capacity of the thermal insulation so proportioned and distributed that the matrix initially assumes the temperature of the hot thermoplastic material.

38. A matrix for forming hot thermoplastic material, comprising a matrix-shell and a matrix-support separated by thermal insulation, the thermal conductivity of the matrix and the thermal capacity of the thermal insulation so proportioned and distributed that the matrix initially assumes the approximate temperature of the hot thermoplastic material, and ultimately cools the same.

39. A matrix for forming hot thermoplastic material, the thermal conductivity of the matrix and the thermal capacity of the matrix-shell so proportioned and distributed with respect to the thermoplastic material, that the matrix initially assumes the temperature of the hot thermoplastic material.

40. A matrix for forming hot thermoplastic material, the thermal conductivity of the matrix and the thermal capacities of the matrix-shell and the matrix-support so proportioned and distributed with respect to the thermal capacity of the thermoplastic material, that the matrix initially assumes the 45 temperature of the hot thermoplastic material.

41. A matrix for forming hot thermoplastic material, the thermal conductivity of the matrix and the thermal capacities of the
55 matrix-shell and the matrix-support so proportioned and distributed with respect to the thermal capacity of the thermoplastic material, that the matrix initially assumes the approximate temperature of the hot
60 thermoplastic material, and ultimately cools the same.

42. A matrix for forming hot thermoplastic material, comprising a matrix-shell and a matrix-support separated by thermal insulation, the thermal conductivity of the

matrix and the thermal capacities of the matrix-support and the insulation so proportioned and distributed with respect to the thermal capacity of the thermoplastic material, that the matrix initially assumes the temperature of the thermoplastic material. 70

43. A matrix for forming hot thermoplastic material, comprising a matrix-shell and a matrix-support separated by thermal insulation, the thermal conductivity of the matrix and the thermal capacities of the matrix-shell, the matrix-support, and the insulation so proportioned and distributed with respect to the thermal capacity of the thermoplastic material, that the matrix initially assumes the approximate temperature of the thermoplastic material, and ultimately cools the same. 75 80

44. A matrix for forming hot thermoplastic material, the thermal conductivity of the matrix and the thermal capacities of the matrix-shell and the matrix-support so proportioned and distributed that it initially assumes the temperature of the hot thermoplastic material. 85 90

45. A matrix for forming hot thermoplastic material, the thermal conductivity of the matrix and the thermal capacities of the matrix-shell and the matrix-support so proportioned and distributed that it initially assumes the approximate temperature of the hot thermoplastic material, and ultimately cools the same.

46. A matrix for forming hot thermoplastic material, the thermal conductivity of the matrix and the thermal capacities of the matrix-support and the insulation so proportioned and distributed that it initially assumes the temperature of the hot thermoplastic material. 100 105

47. A matrix for forming hot thermoplastic material, the thermal conductivity of the matrix and the thermal capacities of the matrix-support and the insulation so proportioned and distributed that it initially assumes the approximate temperature of the hot thermoplastic material, and ultimately cools the same. 110

48. A matrix for forming hot thermoplastic material, the thermal conductivity of the matrix and the thermal capacities of the matrix-shell, the matrix-support and the insulation so proportioned and distributed that it initially assumes the temperature of the hot thermoplastic material. 120

49. A matrix for forming hot thermoplastic material, the thermal conductivity and the thermal capacities of the matrix-shell, the matrix-support and the insulation so proportioned and distributed that it initially assumes the approximate temperature of the hot thermoplastic material, and ultimately cools the same. 125

50. A matrix for forming hot thermoplas. 130

tic material, including a matrix-shell and a backing member separated by insulation, the thermal conductivity of the matrix being so proportioned and distributed to the thermal capacities of the insulation and the thermoplastic material that the matrix initially assumes the temperature of the hot thermoplastic material.

51. A matrix for forming hot thermoplastic material, including a matrix-shell and a backing member separated by insulation, the thermal conductivity of the matrix being so proportioned and distributed to the thermal capacities of the insulation and the thermoplastic material that the matrix initially assumes the approximate temperature of the hot thermoplastic material, and ultimately cools the same.

52. A matrix for forming thermoplastic material, including a matrix-shell and a matrix-support, the thermal conductivity of the matrix-shell and the thermal capacity of the matrix-support being so proportioned and distributed with reference to the thermal capacity of the thermoplastic material, that the matrix-shell initially assumes the temperature of the thermoplastic material.

53. A matrix for forming thermoplastic material, including a matrix-shell and a matrix-support, the thermal conductivity of the matrix-shell and the thermal capacity of the matrix-support being so proportioned and distributed with reference to the thermal capacity of the thermoplastic material, that the matrix-shell initially assumes the approximate temperature of the thermoplastic material, and ultimately cools the same.

54. A matrix for forming hot thermoplastic material, comprising a matrix-shell and a matrix-support separated by thermal insulation, the thermal conductivity of the matrix and the thermal capacities of its matrix-shell and the insulation so proportioned and distributed that the matrix initially assumes the temperature of the hot thermoplastic material.

55. A matrix for forming hot thermoplastic material, comprising a matrix-shell and a matrix-support separated by thermal insulation, the thermal conductivity of the matrix and the thermal capacities of its matrix-shell and the insulation so proportioned and distributed that the matrix initially assumes the approximate temperature of the hot thermoplastic material, and ultimately cools the same.

56. A matrix for forming thermoplastic material, comprising a matrix-shell and a matrix-support separated by thermal insulation, the thermal conductivity of the matrix being so proportioned and distributed with reference to the thermal capacities of its thermoplastic material, the matrix-shell, and

the insulation, that the matrix initially assumes the temperature of the thermoplastic material.

57. A matrix for forming thermoplastic material, comprising a matrix-shell and a matrix-support separated by thermal insulation, the thermal conductivity of the matrix being so proportioned and distributed with reference to the thermal capacities of its thermoplastic material, the matrix-shell, and the insulation, that the matrix initially assumes the approximate temperature of the thermoplastic material, and ultimately cools the same.

58. A matrix for forming thermoplastic material, comprising a matrix-shell and a matrix-support separated by thermal insulation, the thermal conductivity of the matrix being so proportioned and distributed with reference to the thermal capacities of its thermoplastic material, the matrix-support, and the insulation, that the matrix initially assumes the temperature of the thermoplastic material.

59. A matrix for forming thermoplastic material, comprising a matrix-shell and a matrix-support separated by thermal insulation, the thermal conductivity of the matrix being so proportioned and distributed with reference to the thermal capacities of its thermoplastic material, the matrix-support, and the insulation, that the matrix initially assumes the approximate temperature of the thermoplastic material, and ultimately cools the same.

60. A matrix for forming hot thermoplastic material, comprising a matrix shell and a matrix support separated by thermal insulation so proportioned and distributed as to control the initial and final temperatures in different parts of the structure and at different periods in the operation.

61. A matrix for forming hot thermoplastic material, comprising a matrix-shell and a matrix-support separated by thermal insulation so proportioned and distributed as to control the time-interval required for various degrees of heat-flow between different parts of the structure.

62. A matrix for forming hot thermoplastic material, comprising a matrix-shell and a matrix-support separated by thermal insulation so proportioned and distributed as to control both the initial and final temperatures in different parts of the structure and at different periods in the operation, and the time-interval required for various degrees of heat-flow between the different parts of the structure.

Signed at Bridgeport, in the county of Fairfield and State of Connecticut, this 3rd day of May, A. D. 1921.

THEODORE C. ROBERTS.

Certificate of Correction.

It is hereby certified that in Letters Patent No. 1,481,743, granted January 22, 1924, upon the application of Theodore C. Roberts, of New York, N. Y., errors appear requiring correction as follows: In the grant, heading to the printed specification and preamble, title of invention, for the word "Disk" read *Disc* and for "Mediums" read *Media*; page 1, line 14, and page 3, line 11, for the word "disk" read *disc*; page 3, lines 86, 91, 98, 105, 119, and 127, claims 2, 3, 4, 5, 7, and 8, for the words "A means of" read *The method of molding while*; page 5, line 123, claim 49, after the word "conductivity" insert the words *of the matrix*; and that the said Letters Patent should be read with these corrections therein that the same may conform to the record of the case in the Patent Office.

Signed and sealed this 18th day of March, A. D., 1924.
